TOOL HOLDER AND GUARD

Filed June 12, 1943

FIG. 1.

INVENTOR:

JOHN FORMOSA,
by John E. Jackson
his Attorney.

UNITED STATES PATENT OFFICE

2,366,249

TOOLHOLDER AND GUARD

John Formosa, McKees Rocks, Pa.

Application June 12, 1943, Serial No. 490,679

1 Claim. (Cl. 81—1)

This invention relates to a tool holder and guard for hand tools, which must be driven into hard material. When a blow is struck on the head of the tool to force it into the workpiece, fragments of steel from the tool may fly off and hit the operator. If the operator misses the head of the tool, or gives it a glancing blow, injury to his hand often results. If the tool is not held in a vertical direction, there is danger that it will fly from his grasp when the tool is struck by the hammer.

It is an object of this invention to provide a multiple tool holder and guard which will eliminate the dangers set forth above.

This and other objects will be more apparent after referring to the following specification and attached drawing, in which:

Figure 1 is a longitudinal section of the tool holder and guard taken on the line I—I of Figure 2; and

Figure 2 is a top view of Figure 1.

Referring more particularly to the drawing, the reference numeral 2 indicates the hand tools which are shown as steel stamps for stamping letters or numbers on cold steel. A rubber hose 4 has two openings 6 therethrough of appreciably less diameter than the stamps 2 that are held therein, which causes the stamps, when forced into the openings, to displace the body material surrounding them, to thereby cause the material to firmly grip and hold them in an upright position. The operator holds one of the stamps in position for stamping by grasping the rubber hose 4 or the other stamp. This gives him a better grasp on the tool and if the hammer glances from

the tool his hand will not be injured. Surrounding the head portion of the stamps are short sections of rubber hose 8. If the hammer hits the hose, it gives sufficiently to allow the blow to force the stamp into the workpiece. However, if a fragment of steel is struck from the stamp, the hose 8 prevents it from flying toward the operator. In this manner injury to the eye or other exposed portions of the operator's body is prevented.

10 While one embodiment of the invention has been shown and described, it will be apparent that other modifications and adaptations may be made without departing from the scope of the attached claim.

15 I claim:

A tool holder providing a resilient and shock absorbing connection between two or more percussive tools adapted for conjoint use comprising an elongated body of flexible rubber-like material provided with tool receiving openings extending transversely through the side walls thereof and spaced from each other and inwardly from each end of said body, said openings being of appreciably less diameter than the tools to be held therein so as to cause said tools when forced into said openings to displace the body material surrounding said openings and cause said material to firmly grip and hold said tools, and the body portion between said openings forming hand grip portions which, due to the inherent resiliency of said body portion, will prevent percussive shocks from being communicated to the operator.

JOHN FORMOSA.
